UNITED STATES PATENT OFFICE.

WILLIAM A. SCHLEICHER, OF CLEVELAND, OHIO, ASSIGNOR TO THE
EBERHARD MANUFACTURING COMPANY, OF SAME PLACE.

DESIGN FOR A BUCKLE.

SPECIFICATION forming part of Design No. 19,666, dated February 25, 1890.

Application filed January 17, 1890. Serial No. 337,240. Term of patent 14 years.

To all whom it may concern:

Be it known that I, WILLIAM A. SCHLEICHER, of Cleveland, in the county of Cuyahoga and State of Ohio, have invented a new and Original Design for Buckles, of which the following is a full, clear, and exact description, reference being had to the accompanying drawings, forming part of this specification, in which—

10 Figure 1 shows in perspective view a buckle embodying my design. Fig. 2 is a plan view of the same.

15 In the drawings, 2 represents the parallel end bars, which are formed as shown in the drawings, and 3 3 are the side bars. At the corners between the end bars and the side bars the inner edges of the end bars are

notched or indented, and these notches or indentations form essential elements of the design.

20 4 is the cross-bar, which extends between slightly-projecting portions 5 of the side bars.

The part c extends from the cross-bar to one of the end bars, and the side bars are somewhat curved edgewise, as shown in Fig. 2. 25

I claim—

The design for a buckle, substantially as herein described and shown.

In testimony whereof I have hereunto set my hand this 13th day of January, A.D. 1890. 30
WILLIAM A. SCHLEICHER.
